(57) **CLAIM**

The ornamental designs for a catheter pump console interface, as shown and described.

DESCRIPTION

FIG. 1 is a front perspective view of an embodiment of a catheter pump console interface according to the present designs;

FIG. 2 is a rear perspective view of the embodiment of FIG. 1; FIG. 3 is a front elevation view of the embodiment of FIG. 1; FIG. 4 is a rear elevation view of the embodiment of FIG. 1; FIG. 5 is a right-side elevation view of the embodiment of FIG. 1;

FIG. 6 is a left-side elevation view of the embodiment of FIG. 1;

FIG. 7 is a top plan view of the embodiment of FIG. 1; and, FIG. 8 is a bottom plan view of the embodiment of FIG. 1. The broken line showing of portions of the article is included for the purpose of illustrating environmental structure and forms no part of the claimed design.

1 Claim, 5 Drawing Sheets
